UNITED STATES PATENT OFFICE.

ELIHU E. MASSIE, OF PORTSMOUTH, OHIO.

WINDOW-SASH CONTROL.

Application filed November 22, 1924. Serial No. 751,665.

To all whom it may concern:

Be it known that I, ELIHU E. MASSIE, a citizen of the United States, residing at Portsmouth, in the county of Scioto, and 5 State of Ohio, have invented certain new and useful Improvements in Window-Sash Controls; and I do hereby declare the following to be a full, clear, and exact description of the invention, such as will enable others skilled in the art to which it 10 applies to make and use the same.

This invention relates to operating means for window sash whereby the same may be elevated or lowered from the floor without necessitating the mounting of a chair or 15 other article or necessitating the movement of the lower sash when it is required to move the upper sash either into open or closed position.

20 Other objects and advantages will be apparent and suggest themselves as the nature of the invention is understood.

While the drawings illustrate an embodiment of the invention it is to be understood 25 that in adapting the same to meet different conditions and requirements, various changes in the form, proportion and minor details of construction may be resorted to without departing from the nature of the 30 invention.

Referring to the accompanying drawings forming a part of the specification,

Figure 1 is a front view of a window provided with sash operating means embodying the invention,

Figure 2 is a detail sectional view on the line 2—2 of Figure 1, and

Figure 3 is a detail view of the fixture adapted to be attached to the top cross bar 40 of the upper sash.

Corresponding and like parts are referred to in the following description and designated in the several views of the drawings by like reference characters.

45 The numeral 1 denotes a window frame

of ordinary construction provided with sliding sash 2 and 3 which are counterbalanced in the usual or any preferred way. A guide pulley 4 is attached to the upper cross piece or lintel of the window frame 50 1 and an endless sash operating cord 5 passes thereover and extends within convenient reach of the floor to admit of the upper sash 2 being positively moved up or down as required. 55

The fixture attached to the top cross bar of the upper sash 2 comprises a plate 6 and a leaf member 7 pivoted to the plate 6 so as to fold thereagainst or to occupy a position at a right angle thereto as required. 60 The member 7 consists of a plate in which is formed an opening 8, a projection 9 extending laterally into the opening 8 from the outer vertical edge of the opening and spaced from the top, the bottom and the 65 inner vertical edge of the opening. The projection 9 provides for engagement of the sash operating cord 5 with the pivoted member 7 and admits of ready engagement and disengagement of the cord therefrom either 70 for adjustment or to be out of the way when cleaning the window.

What is claimed is:—

Means for positively raising and lowering an upper sash, the same comprising a 75 guide on the window frame, a sash cord trained over said guide, a leaf pivoted to the sash to fold thereagainst to enable maximum movement of the upper sash relatively to the lower sash or to occupy a position at an 80 angle with respect to the upper sash, said leaf having an opening, a lateral projection on said leaf extending into said opening, said cord being detachably applicable into said opening and adapted for disposition across said projection to connect the cord to the leaf. 85

In testimony whereof I affix my signature.

ELIHU E. MASSIE.
